UNITED STATES PATENT OFFICE.

THOMAS E. ADAMS, OF PINE BLUFF, ARKANSAS.

RAILROAD-CAR.

SPECIFICATION forming part of Letters Patent No. 781,119, dated January 31, 1905.

Application filed October 17, 1904. Serial No. 228,804.

To all whom it may concern:

Be it known that I, THOMAS E. ADAMS, a citizen of the United States, residing at Pine Bluff, in the county of Jefferson and State of Arkansas, have invented a new and useful Improvement in Railroad-Cars, of which the following is a specification.

My invention relates particularly to the dead-blocks of a railroad freight-car, and has for its object to provide a rigid and durable dead-block and to prevent the end play of the draft-timbers caused by the strain of the draw-bar. The ordinary dead-block or "dead-wood," which is used as a stop for the horn of the coupler when "buffing," consists of a wooden block having an iron face-plate or angle-piece and attached therewith to the end sill at each end of the car-frame.

My invention consists in substituting for the said wood block and face-plate a dead-block made in one piece, preferably of cast-steel, and having dependent caps for the draft-timbers, as hereinafter particularly described and claimed, reference being had to the accompanying drawings, forming part of this specification, whereon—

Figure 1 is a top plan of my improved combined dead-block and draft-timber end stops or caps as applied to the end sill and draft-timbers, respectively, broken away, of a freight-car; Fig. 2, a longitudinal vertical section thereof on line 2 2 in Fig. 1; Fig. 3, a front elevation thereof; Fig. 4, a vertical longitudinal section through the dead-block and combined caps on line 4 4 in Fig. 1, detached; and Figs. 5, 6, and 7 views corresponding to Figs. 1, 2, and 3, respectively, of an alternative construction of the device.

Like letters and numerals of reference denote like parts in the respective figures.

Referring to Figs. 1, 2, and 3, *a* represents a dead-block, which is composed, preferably, of cast-steel integral throughout and preferably substituted for the ordinary wooden block. The dead-block *a* in the present case consists of a rear plate 1, which bears on its face against the sheathing 2 of the car-body immediately opposite to the middle portion of the end sill 3 in a similar manner to the ordinary wooden block.

Opposite and parallel to the middle portion of the plate 1 at a suitable distance therefrom (corresponding to the thickness of the ordinary wooden block) is an outer or front plate 4. The plates 1 and 4 are preferably united 55 to each other at the bottom part way along the same corresponding to the distance between the draft-timbers *b* or thereabout by a horizontal web 5, having, preferably, holes 5' therethrough and at the ends and immediately thereto, by the upright ribs 6 and 7, respectively, or the dead-block *a* may be otherwise shaped and the metal disposed as found most suitable.

The middle portion of the plate 4, against 65 the outer face of which the horn *c* of the coupler *d* strikes when buffing, is preferably of increased thickness to that of the end portions of the plate 4 for insuring greater strength thereat to the dead-block *a*.

From the bottom of the dead-block *a* depend two vertically-arranged webs 8, which are integral with the block *a*, and preferably in the same plane with the rear plate 1, or the webs 8 may be alined to the front plate 4 75 of the block *a* (as hereinafter more particularly referred to) or intermediately to the plates 1 and 4, as found most suitable.

The depending webs 8 are located opposite to and bear on their rear faces against the outer 80 ends of the draft-timbers *b*, respectively, each web 8 having, preferably, lateral flanges 9 integral therewith, which overlap and extend for a suitable distance along the sides of the corresponding draft-timber *b*, and each web 8 having a bottom flange 10, which is shaped conformably to and bears against the under side of the end portion of the draft-timber *b*, the webs 8, with their flanges 9 and 10, forming 85 stops or caps *e* to the outer ends of the draft-timbers *b*, as shown.

The upright end ribs 6 and adjacent opposite intermediate ribs 7 of the dead-block *a*, which are preferably in the same plane as the lateral flanges 9 of the depending webs 8, are 95 extended downward along the front faces (or reverse to their bearing-faces) of the webs 8 and are united to each other, respectively, across and preferably at the bottom of each web 8 by a horizontal flange 11, all the said parts 100

being integral with each other, and to these flanges 11 on their under sides is fixed the carry-iron 12 for the draw-bar d' by bolts 13.

The dead block a , with the draft-timber stops or caps e and other integral parts of the device, as above described, is secured to the car-frame by the truss-rod bolts 14 and 15, which pass, respectively, through the upper portion of the plate 1 and through the lower lugs or 10 extension 16 of the plate 1 and depending webs 8 in line with the caps e at the outside thereof, and by the bolts 17, which pass upward through the bottom flanges 10 of the caps e , draft-timbers b , end sill 3, and flooring 18 of 15 the car.

In the alternative construction of the dead-block a' shown in Figs 5, 6, and 7 a wooden block 19 is interposed between the front plate 4' and the end sill 3 of the car-frame in lieu 20 of the rear plate 1 and connecting-ribs 6 and 7 of Figs. 1, 2, and 3, the depending vertical webs of the pockets e' in this case being alined to the outer or front plate 4'. Otherwise the 25 general construction and arrangement of the dead-block a' and integral appendages is substantially similar to that shown in Figs. 1, 2, and 3.

By this invention a strong and durable dead-block is obtained, and by the rigid combination therewith of the draft-timber stops or caps e (e') end play of the draft-timbers and shear strain on their fastening-bolts are prevented.

What I claim as my invention, and desire to secure by Letters Patent, is—

In a railroad-car, the combination with the end sill and adjacent draft-timbers, of a dead-block composed of cast-steel integral throughout, and comprising, two opposite plates having an intermediate space and united to each other by cross-pieces, one of the said plates bearing against the face of the end sill and the other plate adapted for engagement by the coupler of the draft-gear, the said block having dependent caps for the draft-timbers, and means for securing the dead-block to the under-frame of the car, substantially as described.

In testimony whereof I have signed my name to this specification in the presence of two subscribing witnesses.

THOMAS E. ADAMS.
